2 SHEETS—SHEET 2.

UNITED STATES PATENT OFFICE.

WILLIAM B. COWLES, OF CLEVELAND, OHIO.

INTERNAL-COMBUSTION ENGINE.

1,053,013.

Specification of Letters Patent. Patented Feb. 11, 1913.

Application filed December 7, 1910. Serial No. 596,157.

To all whom it may concern:

Be it known that I, WILLIAM B. COWLES, a citizen of the United States, residing at Cleveland, in the county of Cuyahoga and State of Ohio, have invented certain new and useful Improvements in Internal-Combustion Engines; and I do hereby declare the following to be a full, clear, and exact description of the invention, such as will enable others skilled in the art to which it appertains to make and use the same.

My present invention relates to internal combustion engines of the compression type and it is especially intended to provide a small, simple and efficient engine adapted for use with automobiles or motor boats, while it is applicable to stationary and marine engines of large size.

In those engines commonly in use at the present day, the ignition is accomplished by an electric spark with the concomitant battery or dynamo and other parts, while the same result is also accomplished by maintaining a constant flame.

According to my present invention I accomplish the ignition by highly and rapidly compressing a small part of the explosive charge, thus doing away with the necessity for the attachments just referred to.

My invention has other important features which will be hereinafter more fully described and claimed.

Reference is had to the accompanying drawings in which the same parts are indicated by the same letters throughout the several views.

Figure 1 shows a central vertical section through the apparatus at the end of the stroke when both the exhaust and inlet ports are open and the supply of explosive gases is being fed to the compression chamber expelling spent gases of the previous explosion. Fig. 2 shows a similar view at the other end of the stroke, parts being shown in elevation. Fig. 3 is a detail view showing the adjustable firing plug for controlling the firing port, and Fig. 4 is a section along the line 4—4 of Fig. 3 and looking in the direction of the arrows.

A represents the casing inclosing the crank, which casing also serves as a receiver for the explosive mixture which enters through the inlet a from the pipe P, past a check valve consisting of the ball P' and spring P².

B represents the crank shaft, C the crank,

D the connecting rod and E the piston body. This piston body includes three separate cylindrical pistons, the main or operating piston E', firing or igniting piston E² and cut-off piston E³. Packing rings e', e², and e³ are provided on the pistons E' and E³, respectively. These pistons are hollow with an axial passage therethrough, as shown most clearly in Fig. 1. The piston E³ is preferably provided with a hollow bushing e³ which serves to bind the packing rings e³ in place and also serves as an inlet port for the passage of the explosive mixture to the compression chamber.

The shell F is provided with an elongated cylindrical chamber F', partly occupied by the piston body but when the piston body is at the limit of its stroke there is still a contracted compression chamber between the surfaces F⁴ and E⁴, as shown in Fig. 2. Beyond this cylindrical chamber F' is a short cylindrical chamber F² for the firing piston, and above this is a cylindrical chamber F³ for the cut-off piston E³. The top of this shell is closed in any suitable way as by the cap f³ and the tap bolts f⁴.

G represents a bushing held in the casing F by means of the bolt g' and by the outer bushing G'. Projecting through these bushings is the stem h² of the firing plug H, which plug is perforated as at h, this stem h² passing through suitable packing h' and preferably terminating in a tail h³ for convenience in turning with a lever. The bushing G is provided with a port g which registers with the port f through the shell into the compression chamber and which registers in whole or in part with the port h in the firing plug H. It will be seen that if the firing plug be turned slightly, the passage from the firing cylinder F² to the compression chamber F³ may be closed in whole or in part, and thus the minimum cross section of the firing port may be varied to suit the requirements of the engine.

The shell F is provided with exhaust ports f⁰ opening into the exhaust passage F⁰ and at the bottom of this exhaust passage a drain plug I is preferably provided. Extending through and around the shell are water cooling passages K, K', K² and K³, the water being fed through the inlet k and circulating in the usual well known way. Any suitable form of water jacket 110 may be used if desired, and I do not claim this as a part of my present invention.

The operation is as follows:—Suppose the apparatus to be in the position shown in Fig. 2 and the mixture in the compression chamber be exploded, this will force the piston body downward until the exhaust ports are open and the spent gases will rush through said ports and escape. Following quickly the fall of pressure and the escape of spent gases, the cut-off piston E³ will pass clear of the cylinder F³ permitting the flow of unexploded mixture into the compression chamber; this will drive out before it the residue of spent gases; and about the time the compression chamber is completely free of spent gases, the return of the main piston will close the exhaust ports. Shortly before this, the piston E³ will project into the cylinder F³ and close the inlet ports leaving the compression chamber duly charged. As the piston body continues its travel the mixture will be compressed in the compression chamber, and as the piston body nears the end of its stroke, the firing piston E² will pinch off a part of the explosive charge and will compress same in the firing cylinder F² until it reaches the ignition temperature, when there will be an explosion, and the flame or heated gases will pass through the firing port and entering the compression chamber will explode the compressed gases in said chamber, thus renewing the cycle of operations.

It will be noted that the piston body E is substantially in the shape of a bottle open at the top and bottom, with a curved portion E⁴ at the base of the neck E³ of the bottle, the cylinder F² above which curved portion constitutes the firing piston. The neck portion E³ of the bottle shaped piston body, which I have called the cut-off piston, serves not only as a cut-off for the explosive mixture during the compression period, but also as the inner wall of the compression chamber after the explosion has taken place, effectually preventing the return back to the interior of the piston of any of the hot gases produced by the explosion, until after the exhaust ports are wide open, when the excess of pressure in the receiver will tend to blow the expanded and greatly cooled spent gases out through said ports. It will be noted that there will be a great rush of the exploded gases to escape out through the exhaust ports as soon as these ports begin to open, and that the small quantity of expanded and comparatively cool spent gases left in the compression chamber will be blown out by the incoming explosive mixture.

Thus I provide an internal combustion engine in which the cylinder, compression chamber, and ports are completely cleared or "scavenged" by a direct rush of the gases after explosion and while charging the compression chamber. There are no

pockets to retain and no eddies formed tending to retain solid or gaseous residue inside the cylinder. The walls of the compression chamber are cooled not only by the water jacket but also by the flow of the incoming explosive gases, which cool on expanding, and passing through the cut-off piston keep the temperature below the ignition point when the inlet port is open. It will therefore be evident that it will be impossible with this engine to accidentally ignite the charge in the compression chamber while the inlet port is open; and thus the serious difficulty, known as back-firing, common to many of the gasoline motors now in use, is wholly obviated. It will be further noted that the packing rings e⁴ near the end of the cut-off piston E³ and the packing rings e¹ and e² on the main piston E', serve not only to guide and steady the whole piston body, and incidentally the firing piston E², but also render it possible to dispense with packing rings on said firing piston. Packing rings, however, may be provided for it if desired.

It will be obvious that various modifications may be made in the herein-described apparatus which could be used without departing from the spirit of my invention.

Having thus described my invention, what I claim and desire to secure by Letters Patent of the United States, is:—

1. An internal combustion engine of the compression type comprising a receiver for the explosive mixture, a hollow shell closed at one end and opening at the other into said receiver, said shell being provided with a series of stepped cylindrical chambers, and decreasing in diameter away from said receiver, a hollow piston body perforated axially and provided with a series of cylindrical pistons registering with said chambers, respectively, and a firing port connecting the outer end of one of said reduced cylinders with the compression chamber, substantially as described.

2. An internal combustion engine of the compression type comprising a receiver for the explosive mixture, a hollow shell closed at one end and opening at the other into said receiver, said shell being provided with a series of stepped cylindrical chambers decreasing in diameter away from said receiver, a hollow piston body perforated axially and provided with a series of cylindrical pistons registering with said chambers, respectively, and a firing port connecting the outer end of one of said reduced cylinders with the compression chamber with means for adjusting the cross-section of said firing port, substantially as described.

3. An internal combustion engine of the compression type comprising a piston rod, a hollow piston body open at both ends and connected to said rod, said piston body hav-

ing a main piston, a firing piston of less diameter connected thereto, and a cut off piston of less diameter than either of said pistons connected to said firing piston, means 5 for supplying the explosive mixture to the interior of said hollow piston body, and a shell provided with a cylindrical chamber for the main piston and for the compression chamber, with a short cylindrical firing 10 chamber registering with the firing piston toward the end of its stroke, with a longer cylindrical chamber registering with and engaging said cut off piston during the major portion of its stroke, and with a firing 15 port connecting said firing chamber, and said compression chamber, substantially as described.

4. An internal combustion engine of the compression type comprising a piston rod, 20 a hollow piston body open at both ends and connected to said rod, said piston body having a main piston, a firing piston of less diameter connected thereto, and a cut off piston of less diameter than either of said pistons 25 tons connected to said firing piston, means for supplying the explosive mixture to the interior of said hollow piston body, and a shell provided with a cylindrical chamber for the main piston and for the compression 30 chamber, with a short cylindrical firing chamber registering with the firing piston toward the end of its stroke, with a longer cylindrical chamber registering with and engaging said cut off piston during the major 35 portion of its stroke, and with a firing port connecting said firing chamber, and said compression chamber, with means for varying the minimum cross-section of said firing port, substantially as described.

40 5. An internal combustion engine of the compression type comprising a piston rod, a hollow piston body open at both ends and connected to said rod, said piston body having a main piston, a firing piston of less diameter connected thereto, and a cut off piston of less diameter than either of said pistons connected to said firing piston, means for supplying the explosive mixture to the interior of said hollow piston body, and a shell 45 provided with a cylindrical chamber for the main piston and for the compression chamber, with a short cylindrical firing chamber registering with the firing piston toward the end of its stroke, with a longer cylindrical 50 chamber registering with and engaging said cut off piston during the major portion of its stroke, and with a firing port connecting said firing chamber, and said compression chamber, with a rotatable firing plug 55 provided with a passage therethrough normally registering with said firing port but adapted to throttle down said firing port, substantially as described.

60 6. An internal combustion engine of the compression type comprising a receiver for 65

the explosive mixture, a hollow shell closed at one end and opening at the other into said receiver, said shell being provided with a series of stepped cylindrical chambers, and decreasing in diameter away from said receiver, a hollow piston body perforated axially and provided with a series of cylindrical pistons registering with said chambers, respectively, a firing port connecting the outer end of one of said reduced cylinders 70 with the compression chamber, and means for cooling the outer walls of said compression chamber, substantially as described.

7. An internal combustion engine of the compression type comprising a receiver for 80 the explosive mixture, a hollow shell closed at one end and opening at the other into said receiver, said shell being provided with a series of stepped cylindrical chambers decreasing in diameter away from said receiver, a hollow piston body perforated axially and provided with a series of cylindrical pistons registering with said chambers, respectively, a firing port connecting the outer end of one of said reduced cylinders 85 with the compression chamber with means for adjusting the cross-section of said firing port, and means for cooling the outer walls of said compression chamber, substantially 90 as described.

95 8. An internal combustion engine of the compression type comprising a piston rod, a hollow piston body open at both ends and connected to said rod, said piston body having a main piston, a firing piston of less diameter connected thereto, and a cut off piston of less diameter than either of said pistons connected to said firing piston, means for supplying the explosive mixture to the interior of said hollow piston body, and a 100 shell provided with a cylindrical chamber for the main piston and for the compression chamber, with a short cylindrical firing chamber registering with the firing piston toward the end of its stroke, with a longer 105 cylindrical chamber registering with and engaging said cut off piston during the major portion of its stroke, with a firing port connecting said firing chamber, and said compression chamber, and means for cooling the 110 outer walls of said compression chamber, substantially as described.

115 9. An internal combustion engine of the compression type comprising a piston rod, a hollow piston body open at both ends and connected to said rod, said piston body having a main piston, a firing piston of less diameter connected thereto, and a cut off piston of less diameter than either of said pistons connected to said firing piston, means 120 for supplying the explosive mixture to the interior of said hollow piston body, and a shell provided with a cylindrical chamber for the main piston and for the compression 125 chamber, with a short cylindrical firing

130

chamber registering with the firing piston toward the end of its stroke, with a longer cylindrical chamber registering with and engaging said cut off piston during the major portion of its stroke, with a firing port connecting said firing chamber, and said compression chamber, with means for varying the minimum cross-section of said firing port, and means for cooling the outer walls of said compression chamber, substantially as described.

10. An internal combustion engine of the compression type comprising a piston rod, a hollow piston body open at both ends and connected to said rod, said piston body having a main piston, a firing piston of less diameter connected thereto, and a cut off piston of less diameter than either of said pistons connected to said firing piston, means for supplying the explosive mixture to the interior of said hollow piston body, and a shell provided with a cylindrical chamber for the main piston and for the compression chamber, with a short cylindrical firing chamber registering with the firing piston toward the end of its stroke, with a longer cylindrical chamber registering with and engaging said cut off piston during the major portion of its stroke, with a firing port connecting said firing chamber, and said compression chamber, with a rotatable firing plug provided with a passage therethrough normally registering with said firing port but adapted to throttle down said firing port, and means for cooling the outer walls of said compression chamber, substantially as described.

11. A two cycle internal combustion engine of the compression type comprising a crank shaft and crank, a connecting rod, a receiver for the explosive mixture inclosing said crank shaft and crank, a hollow shell closed at one end and opening at the other into said receiver, said shell being provided with a series of stepped cylindrical chambers, and decreasing in diameter away from said receiver, a hollow piston body perforated axially and provided with a series of cylindrical pistons registering with said chambers, respectively, said piston body being connected to said connecting rod, and a firing port connecting the outer end of one of said reduced cylinders with the compression chamber, substantially as described.

12. A two cycle internal combustion engine of the compression type comprising a crank shaft and crank, a connecting rod, a receiver for the explosive mixture inclosing said crank shaft and crank, a hollow shell closed at one end and opening at the other into said receiver, said shell being provided with a series of stepped cylindrical chambers decreasing in diameter away from said receiver, a hollow piston body perforated axially and provided with a se-

ries of cylindrical pistons registering with said chambers, respectively, said piston body being connected to said connecting rod, and a firing port connecting the outer end of one of said reduced cylinders with the compression chamber with means for adjusting the cross-section of said firing port, substantially as described.

13. A two cycle internal combustion engine of the compression type comprising a crank shaft and crank, a connecting rod, a receiver for the explosive mixture inclosing said crank shaft and crank, a hollow shell closed at one end and opening at the other into said receiver, said shell being provided with a series of stepped cylindrical chambers, and decreasing in diameter away from said receiver, a hollow bottle shaped piston body perforated axially and provided with a series of cylindrical pistons registering with said chambers, respectively, said piston body being connected to said connecting rod, a firing port connecting the outer end of one of said reduced cylinders with the compression chamber, and means for cooling the outer walls of said compression chamber, substantially as described.

14. A two cycle internal combustion engine of the compression type comprising a crank shaft and crank, a connecting rod, a receiver for the explosive mixture inclosing said crank shaft and crank, a hollow shell closed at one end and opening at the other into said receiver, said shell being provided with a series of stepped cylindrical chambers decreasing in diameter away from said receiver, a hollow bottle shaped piston body perforated axially and provided with a series of cylindrical pistons registering with said chambers, respectively, said piston body being connected to said connecting rod, a firing port connecting the outer end of one of said reduced cylinders with the compression chamber with means for adjusting the cross-section of said firing port, and means for cooling the outer walls of said compression chamber, substantially as described.

15. In an internal combustion engine of the compression type, the combination with a main cylinder and piston and a compression chamber, of a firing cylinder and piston adapted to cut off and compress to the ignition point a small portion of the explosive charge, and a firing port connecting said firing cylinder with said compression chamber with means for varying the minimum cross section of said firing port, substantially as described.

16. In an internal combustion engine of the compression type, the combination with a main cylinder and piston and a compression chamber, of a firing cylinder and piston adapted to cut off and compress to the ignition point a small portion of the explosive charge, a firing port connecting said firing

cylinder with said compression chamber with means for varying the minimum cross section of said firing port, said means comprising a firing port in the walls of said cylinder, and a firing plug having a port adapted to register in whole or in part with said firing port, substantially as described.

17. An internal combustion engine of the compression type comprising a piston rod, 10 a hollow piston body open at both ends and connected to said rod, said piston body having a main piston, a firing piston of less diameter connected thereto, and a cut off piston of less diameter than either of said 15 pistons connected to said firing piston, means for supplying the explosive mixture to the interior of said hollow piston body, and a shell provided with a cylindrical chamber for the main piston and for the 20 compression chamber, with a short cylindrical firing chamber registering with the firing piston toward the end of its stroke, and with a longer cylindrical chamber registering with and engaging said cut off piston 25 ton during the major portion of its stroke, substantially as described.

18. An internal combustion engine of the compression type comprising a piston rod, a hollow piston body open at both ends and 30 connected to said rod, said piston body having a main piston, a firing piston of less diameter connected thereto, and a cut off piston of less diameter than either of said 35 pistons connected to said firing piston, means for supplying the explosive mixture to the interior of said hollow piston body, and a shell provided with a cylindrical chamber for the main piston and for the 40 compression chamber, said shell having exhaust ports opening from said main cyl-

inder near the inner end thereof, the said shell being also provided with a short cylindrical firing chamber registering with the firing piston toward the end of its stroke, and with a longer cylindrical chamber reg- 45 istering with and engaging said cut off piston during the major portion of its stroke, substantially as described.

19. An internal combustion engine of the compression type comprising a piston rod, 50 a hollow piston body open at both ends and connected to said rod, said piston body having a main piston, a firing piston of less diameter connected thereto, and a cut off piston of less diameter than either of said 55 pistons connected to said firing piston, means for supplying the explosive mixture to the interior of said hollow piston body, and a shell provided with a cylindrical chamber for the main piston and for the 60 compression chamber, said shell having exhaust ports opening from said main cylinder near the inner end thereof, the said shell being also provided with a short cylindrical firing chamber registering with the firing 65 piston toward the end of its stroke, and with a longer cylindrical chamber registering with and engaging said cut off piston during the major portion of its stroke, the said shell being provided with a firing port connecting said firing chamber; and said compression chamber, substantially as described.

In testimony whereof, I affix my signature, in presence of two witnesses.
